UNITED STATES PATENT OFFICE.

GEORGE OTIS DRAPER, OF HOPEDALE, MASSACHUSETTS, ASSIGNOR TO DRAPER COMPANY, OF HOPEDALE, MASSACHUSETTS, A CORPORATION OF MAINE.

RING-SPINNING APPARATUS.

SPECIFICATION forming part of Letters Patent No. 768,846, dated August 30, 1904.

Application filed March 30, 1904. Serial No. 200,661. (No model.)

To all whom it may concern:

Be it known that I, GEORGE OTIS DRAPER, a citizen of the United States, and a resident of Hopedale, county of Worcester, State of Massachusetts, have invented an Improvement in Ring-Spinning Apparatus, of which the following description, in connection with the accompanying drawings, is a specification, like characters on the drawings representing like parts.

This invention relates to ring-spinning apparatus; and it has for its object the production of means for steadyng the traveler as it revolves around the ring, whereby the traveler will run with greater ease and uniformity and with a reduction in the friction at the inner end of the traveler, so that higher speeds may be employed.

In the ordinary operation of ring-spinning the centrifugal force acts to throw the traveler outward and force its inner end against the inner flange of the ring, while the pull of the yarn tends to tip the traveler and lift its outer end, the greater part of the wear being borne by the inner end of the traveler. The pull or strain of the yarn in spinning is constantly varying, due to the traverse motion of the frame and the different diameters of the bobbin onto which the yarn is laid, so that the traveler has a rocking and unsteady motion, the outer end of the traveler rising and falling as the yarn-pull increases and decreases. The higher the speed the more frequent the rocking motion of the traveler and the greater will be the wear on the inner end thereof, owing to the increased centrifugal force exerted.

In accordance with my present invention I have provided means to coöperate with and vertically support the outer end of the traveler during its revolutions around the fixedly-held ring, so that the motion of the traveler is made steady and substantially uniform irrespective of the spindle speed or changes in the pull of the yarn.

The novel features of my invention will be fully described in the subjoined specification

and particularly pointed out in the following claims.

Figure 1 in side elevation and partial section represents a sufficient portion of a yarn-spinning apparatus to be understood with one form of my invention embodied therein. Fig. 2 is an enlarged cross-section of the ring shown in Fig. 1. Fig. 3 is a view similar to Fig. 1 of a modification to be described, and Fig. 4 is an enlarged cross-section of the ring shown in Fig. 3.

In Fig. 1 the ring-rail 1, spindle 2, and ring-holder 3, attached to the ring-rail in usual manner, may be and are all of well-known construction to those familiar with ring-spinning apparatus. The ring is of the non-rotative, reversible, or so-called "double-flange" type, comprising a circular web 4, having at its top and bottom inner flanges 5 and oppositely-located outer flanges 6, either pair of oppositely-extended flanges constituting a race for the traveler, the outer flange of the other pair at such time being engaged by the holder 3 to retain the ring from rotation. The traveler 9 is of usual construction and has its ends bent and inturned toward each other, as at 10 11, to coöperate with the race, the end 10 fitting over the outer flange and end 11 over the inner flange 5 of the ring, the yarn *t* passing through the traveler to the bobbin. I have provided a fixed annular rest for and to vertically support the outer end of the traveler during its revolution around the ring, and in Figs. 1 and 2 I have shown such rest as integral with the ring. To this end the web 4 is provided with an external rib or projection 7 between the two outer flanges 6, the upper and lower faces 8 of such projection being flat, smooth, and in parallelism with each other and with the flanges. The projection extends laterally beyond the peripheries of the outer flanges 6, and its faces 8 are located quite near the under faces of such flanges, but far enough away therefrom to avoid any tendency to clamp or hold the traveler.

As will be manifest from an inspection of Fig. 1, the upper face of the annular projec-

tion 7 forms a fixed rest for and upon which the outer end 10 of the traveler slides, vertically supporting the traveler exterior to the ring and distributing the wear. The traveler 5 is maintained in a more nearly upright position, and by supporting its outer end throughout its circular path of movement the traveler cannot rock or move unsteadily owing to variations in the yarn pull, and as the traveler 10 is thus in a measure balanced and its movement rendered more uniform and the wear more equally distributed over both ends of the traveler the latter will last longer and can be run with a higher spindle speed.

15 In the modification shown in Figs. 3 and 4 the web 12 of the ring is reduced in height and each of the outer flanges 13 is somewhat thickened, so that the lower one of said flanges serves as a rest, the outer end of the traveler 20 being supported by the upper flat face 14 of the rest-forming flange. This ring can be reversed, as will be obvious, the uppermost outer flange 13 and the opposite inner flange 15 constituting the traveler-race, as shown in 25 Fig. 3. With the modified ring shown the form of ring-holder illustrated in Fig. 1 could not be employed, as the holding-lips would interfere with the movement of the traveler; but some other suitable holding means could 30 be employed—as, for instance, a ring 16, secured to the ring-rail and having an upturned lip 17 (see dotted lines, Fig. 3) to fit within the lower inner flange 15.

Having fully described my invention, what 35 I claim as new, and desire to secure by Letters Patent, is—

1. A reversible double-flanged spinning-ring, each set of inner and outer flanges forming a traveler-race, and an outwardly-extended, fixed annular projection between the upper and lower outer flanges, to form a rest for the outer end of the traveler when the latter 40 coöperates with either race.

2. A reversible double-flanged spinning-ring and an external annular projection integral therewith and projecting laterally beyond the outer flanges of the ring, said projection 45 forming a rest to support and steady the outer

end of the traveler when the latter coöperates with the double flanges at either the top or bottom of the ring.

3. In combination, a non-rotative reversible spinning-ring having oppositely-extended flanges at the top and bottom thereof, a flat-faced annular traveler-rest integral with the 55 ring and located between the outer flanges thereof, and a traveler adapted to be supported at its outer end by the uppermost face of said rest when the traveler is in coöperation with either pair of the oppositely-extended flanges. 60

4. A non-rotative spinning-ring comprising a web and oppositely-extended annular flanges at both top and bottom of the web, and an external projection on and integral with the web and symmetrically disposed with relation 65 to the outer flanges thereof and extended laterally beyond the peripheries of said outer flanges.

5. A spinning-ring comprising a web and oppositely-extended annular flanges at top 70 and bottom of the web, and an external projection on and integral with the web and symmetrically disposed with relation to the outer flanges thereof, the upper and lower faces of said projection being parallel to each other 75 and extended laterally beyond the peripheries of the outer flanges, one or the other face being adapted to support the outer end of a traveler when coöperating with the oppositely-extended pair of flanges above the projection.

6. A reversible spinning-ring having inner and outer horizontal flanges forming a race for the traveler, a traveler coöperating therewith, a ring-holder to engage and retain the 85 ring from rotation, and an annular fixed rest on and exterior to the ring and adapted to vertically support the outer end of and steady the traveler.

In testimony whereof I have signed my name 90 to this specification in the presence of two subscribing witnesses.

GEORGE OTIS DRAPER.
